US0D1074455S

(12) **United States Design Patent** (10) **Patent No.:** **US D1,074,455 S**
(45) **Date of Patent:** **** May 13, 2025**

(54) **BOTTLE CARRIER FOR TRANSPORT**

(71) Applicant: **DS SMITH PACKAGING LTD,**
London (GB)

(72) Inventors: **Wim Wouters**, Herresbach (BE); **Peter Pieraets**, Leuven (BE); **Carlos Diaz**, Brussels (BE); **Ádám Horváth**, Sopron (HU)

(**) Term: **15 Years**

(21) Appl. No.: **35/518,395**

(22) Filed: **Sep. 22, 2022**

(80) **Hague Agreement Data**

Int. Filing Date: **Sep. 22, 2022**

Int. Reg. No.: **DM/224084**

Int. Reg. Date: **Sep. 22, 2022**

Int. Reg. Pub. Date: **Sep. 22, 2023**

(51) **LOC (15) Cl.** **09-03**

(52) **U.S. Cl.**

USPC **D9/753**

(58) **Field of Classification Search**

USPC D9/719, 751-753

CPC B65D 71/50; B65D 2571/0066;
B65D 71/40; B65D 71/406

Primary Examiner — W. A. Teddy Falloway

(57) **CLAIM**

The ornamental design for a bottle carrier for transport as shown and described.

DESCRIPTION

1. Bottle carrier for transport
  4. Bottle carrier for transport
  - 1.1 : Perspective
  - 1.2 : Front
  - 1.3 : Back
  - 1.4 : Right
  - 1.5 : Left
  - 1.6 : Top
  - 1.7 : Bottom
  - 4.1 : Perspective
  - 4.2 : Front
  - 4.3 : Back
  - 4.4 : Right
  - 4.5 : Left
  - 4.6 : Top
  - 4.7 : Bottom
- The broken lines shown represent fold lines and form no part of the claimed design.

1 Claim, 14 Drawing Sheets
